GORHAM MANUFACTURING CO.

ASSIGNEES OF

GEORGE WILKINSON'S

"Mask" Design for the Handle of Spoons, Forks and other Table Ware.

N°. 2997

PATENTED
APR 7 1868

Witnesses, *Asaac A. Bonnell* ^{Inventor, Geo. Wilkinson}
Gorham *Thimble*

United States Patent Office.

GEORGE WILKINSON, OF PROVIDENCE, RHODE ISLAND, ASSIGNOR TO THE GORHAM MANUFACTURING COMPANY, OF SAME PLACE.

Design No. 2,997, dated April 7, 1868.

DESIGN FOR A FORK OR SPOON-HANDLE CALLED "MASK."

The Schedule referred to in these Letters Patent and making part of the same.

TO ALL WHOM IT MAY CONCERN:

Be it known that I, GEORGE WILKINSON, of the city and county of Providence, and State of Rhode Island, have originated a new Design for Articles of Silver, and other metals and plated ware, of which the following is a full, clear, and exact description, reference being had to the accompanying specimens or drawings, making part of this specification; that is to say, for a design, called the "Mask," for the handles of spoons, forks, and other table-ware and implements, of which—

Figure 1 is a view of the front side of said design,

Figure 2 is a view of the back side of the same, and

Figure 3 is a side view of the same.

Similar letters indicate corresponding parts in all the figures.

My said design consists of a "mask," suitably mounted at the end of a handle or stem, of the requisite shape and proportions to receive the same, and conform to the style and uses of the spoon or other implement.

In the drawings, M is the mask, at the end of the handle, L, of the spoon, with a bowl, B, of suitable shape and proportion for a sugar-spoon or berry-spoon. The "mask," it will be seen, is mounted on the extreme end of the handle L, which is bent at f, fig. 3, to support and mount the "mask" in the best manner to produce the desired effect and relief of it as a design, or a prominent and marked feature thereof. The stem of the handle is round or cylindrical, and perfectly plain, except the ornamental collar, n, from which, as the handle proceeds towards the bowl of the spoon, or, if a fork be substituted for such bowl, the handle is flattened, and increases in substance to where it merges into the spoon or fork.

Claim.

I claim the design for the handles of spoons, forks, and other similar implements, substantially as set forth and shown.

GEO. WILKINSON.
